UNITED STATES PATENT OFFICE.

CHARLES J. ZILLGITT AND WALTER K. STEBBINS, OF FAIRMOUNT, NORTH DAKOTA.

FLUE-CUTTER.

No. 903,941.

Specification of Letters Patent.

Patented Nov. 17, 1908.

Application filed February 21, 1908. Serial No. 417,106.

To all whom it may concern:

Be it known that we, CHARLES J. ZILLGITT and WALTER K. STEBBINS, citizens of the United States, residing at Fairmount, in the 5 county of Richland and State of North Dakota, have invented certain new and useful Improvements in Flue-Cutters, of which the following is a specification.

The present invention has for its object 10 to devise a boiler flue cutter of novel form and which will be simple in construction, efficient in operation and comprise a minimum number of parts.

In its construction, the device comprises a 15 rotary head adapted to be inserted in the flue to be cut from the head or sheet of the boiler, said head being slotted and provided with anti-friction rollers and an adjustable slide, the latter being supplied with a rotary 20 cutter, a frame for fixing the position of the tool when applied to the end of the flue to be cut, said frame being connected to the rotary head by means of a swivel joint, and a pin or shaft slidably mounted in the rotary 25 head and having an inclined way to co-operate with the slide bearing the rotary cutter, so as to advance the same to the work and at the same time insure rotation of the head when turning the pin or shaft to carry 30 the cutter around the inner wall of the flue.

For a full understanding of the invention and the merits thereof and also to acquire a knowledge of the details of construction and the means for effecting the result, reference 35 is to be had to the following description and accompanying drawings.

While the invention may be adapted to different forms and conditions by changes in the structure and minor details without departing from the spirit or essential features thereof, still the preferred embodiment is shown in the accompanying drawings, in which:

Figure 1 is a perspective view of a boiler 45 flue cutter embodying the invention. Fig. 2 is a central longitudinal section of the tool. Fig. 3 is a transverse section on the line $\alpha-\alpha$ of Fig. 2. Fig. 4 is a detail perspective view of the slide. Fig. 5 is a sectional detail 50 tail of a portion of the shaft, the radially adjustable slide provided with the rotary cutter and the outer confining ring, the slide and cutter being shown in full lines.

Corresponding and like parts are referred 55 to in the following description and indicated

in all the views of the drawings by the same reference characters.

The rotary head 1 has an end portion reduced forming a shoulder 2 and is provided with a series of slots in which rollers 3 and 60 a slide 4 are fitted. The rollers 3 maintain a fixed relation with reference to the rotary head and serve simply to reduce the friction between said head and the flue to be cut. The slide 4 is adjustable radially and is provided with a rotary cutter 5. The several slots are closed at their outer ends by means of a ring 6. A frame 7 is fitted upon the reduced end of the rotary head and is confined 65 between the shoulder 2 and a collar 8, the latter 70 being slipped upon a projecting end of the reduced portion of the head 1 and secured thereto by means of a pin 9 or in any substantial way. The frame 7 is free to rotate upon the rotary head and serves to fix the 75 position of the tool when fitted to the flue to be cut. The slide 4 consists of a block and is provided at its ends with ribs 10 which are mounted in grooves 11 at opposite ends of the slot in which the slide 4 is fitted. The 80 ribs 10 and grooves 11 form guides to properly direct the slide in its movements and prevent the rotary cutter 5 from coming in contact with the side walls of the slot in which the slide 4 is placed. The inner groove 85 11 is formed in the head 1, whereas the outer groove is formed in the ring 6. A cross head 12 is provided at the inner end of each rib 10 to limit the outward movement of the slide 4.

The operating pin or shaft 13 is slidable 90 within the rotary head 1 and is provided in a side with a longitudinally tapered groove 14 which receives the inner end of the slide 4. A stop 15 is provided at the outer end of the groove 14 to engage with the slide 4 and 95 limit the relative outward movement of the pin or shaft 13. A stop 16 projected laterally from the pin or shaft 13 near the outer end thereof, is adapted to engage with the rotary head 1 and limit the inward movement of said pin or shaft. The groove 14 constitutes an inclined way or seat in which the inner end of the slide 4 is fitted so that upon pressing the pin or shaft 13 inward, the slide 4 riding upon the inclined way provided 100 by the groove 14, is moved outward, thereby advancing the rotary cutter 5 to its work. Any suitable means may be resorted to for 105 rotating the pin or shaft 13 and for this purpose openings 17 formed in the outer end 110

portion of the pin or shaft 13, are adapted to receive a rod or like implement, whereby leverage is provided for both turning the tool and forcing the pin or shaft 13 inward. The 5 set pin or shaft 13 may be forced inward by tapping the outer end thereof by means of a hammer or other tool.

Having thus described the invention, what is claimed as new is:

- 10 In a tool of the character set forth, the combination of a rotary head having open ended slots formed in an end portion thereof, a ring secured to said rotary head and closing the outer ends of said slots, rollers fitted 15 in certain slots, a slide mounted in another one of the slots and provided with a rotary

cutter, ribs at the ends of the slide mounted in grooves in the end walls of the slot in which the slide is arranged, said ribs having cross heads at their inner ends to form stops, 20 a frame connected to the rotary head by a swivel joint, and an operating pin or shaft mounted in the rotary head to slide therein and having a longitudinally tapered groove to receive the inner end of the said slide. 25

In testimony whereof we affix our signatures in presence of two witnesses.

CHARLES J. ZILLGITT. [L. S.]
WALTER K. STEBBINS. [L. S.]
